E. RITTER

ELECTRIC VAPORIZER

Filed Dec. 3, 1924

UNITED STATES PATENT OFFICE.

EDWARD RITTER, OF NEW YORK, N. Y.

ELECTRIC VAPORIZER.

Application filed December 3, 1924. Serial No. 753,664.

To all whom it may concern:

Be it known that I, EDWARD RITTER, a citizen of the United States, residing at New York city, borough of Manhattan, in the county of New York and State of New York, have invented certain new and useful Improvements in Electric Vaporizers, of which the following is a specification.

This invention relates to incense or perfume dispensers and more particularly to devices of that nature which operate in conjunction with a heating unit.

Among the objects of this invention is to provide an incense or other perfume or fluid dispenser which is mounted adjacent to a heating unit so that the rate of evaporation of the fluid is greatly increased, said dispenser comprising a casing for fixing the rate of evaporation.

Another object of this invention is to provide a device for dispensing any fluid in the form of a vapor or a gas, said device comprising for this purpose a heating unit for evaporating the fluid, and a casing for enveloping said fluid and said heating unit to conserve the heat for the sake of economical and efficient operation.

Another object of this invention is to provide a gas or vapor dispenser in connection with a lamp comprising means for containing a fluid, and a casing to support said fluid container in movable relation so as to permit said casing and said lamp to be mounted in upright or in downwardly directed position while the fluid containing means is always in upright position to contain the fluid.

Still another object of this invention is to provide in connection with a lamp or the like, a fluid dispenser to utilize the heat thereof for purposes of evaporation or gassification, said dispenser comprising heat enveloping means comprising a plurality of parts having novel engagement with each other and with the container for the fluid.

With the foregoing and other objects in view the invention consists in the arrangement and combination of parts hereinafter described and claimed and while the invention is not restricted to the exact details of construction disclosed or suggested herein, still for the purpose of illustrating a practical embodiment thereof reference is had to the accompanying drawings in which like

reference characters designate the same parts in the several views, and in which—

Figure 1 is an elevational cross-section of the device looking in the direction of line 1—1 of Fig. 2.

Fig. 2 is an external view of the device. 60

Fig. 3 is a sectional view of the device mounted in a different position, parts thereof being broken away.

Fig. 4 is a sectional view on the line 4—4 of Fig. 1. 65

Referring now more specifically to the drawings, I show the fluid dispenser comprising a heating unit, such as a lamp 10 or the like which is operative preferably by electricity, supplied through a suitable plug connection such as a standard base or plug 11. Mounted adjacent to the lamp is a fluid container 12 which is constructed preferably of an annular form so as to receive a portion of the lamp body within the inner walls 13 thereof. A heat enveloping means, such as a casing 14 is used to cover both the lamp and the fluid containing means so as to control the circulation of air about said containing means, thereby conserving the heat of said lamp, and controlling the rate of evaporation of the fluid. 75

Said heat enveloping means comprises preferably an extension of neck 15 at an end of which the standard plug 11 is formed, as about the annular portion or shoulder 16 to which the threaded metallic thimble 17 is secured by means such as cement 18. The circuit for the lamp is made in the usual manner through wires 19 and 20 having contact respectively with said thimble and with a center contact 21 which is supported by suitable insulation 22. Mounted along said neck is a means spaced from the plug aforesaid and having electrical engagement with said plug and said lamp for supplying current to the latter. This takes preferably the form of a socket 23 for receiving the base or plug 24 of the lamp, said socket being secured to a porcelain base 25 as by means of screws 26 having engagement with the lugs 27 of said socket. A central spring contact 28 is also provided to complete the circuit therethrough and through the screw 29 which supports the same in the usual manner. This socket arrangement is mounted in any suitable manner, though it is cemented in place by cement placed within 80

the clearance between the base and the wall of the neck. As a means for insulating said socket arrangement from direct contact with the hot gases within the casing 14, insulation such as a plate or disk of mica 30 is provided which is preferably threaded upon said socket, and is of somewhat larger diameter than the neck 15 so as to abut against the converging sides of said casing as shown 5 at 31, thus making an effective gas seal. Referring again to the plug 11 in connection with the socket 23, it will be seen that my invention comprehends the principle of arranging in conjunction with a heating unit such 10 as an electric lamp and means for providing a relatively static and high temperature heat zone about the lamp, of a plurality of connectors such as a plug and socket which are in electrical circuit, one of them such as the 15 plug having connection with a line circuit or the like, while the other has connection with said lamp for supplying current thereto, said plug and socket being spaced from each other whereby the former is positioned 20 more remotely from said heating unit to be less affected by the heat thereof. This arrangement also permits of the ready insertion or removal of a lamp, and, as specifically disclosed, provides a neat and inexpensive 25 construction and one which is highly adapted for the uses to which this invention can be put.

The fluid container 12 is mounted in a suitable manner within the heat and evaporation controlling means 14, and preferably upon a casing part or device having detachable engagement with said means. More specifically, said device takes the form preferably of a cover 32 which is provided with 30 lugs 23 formed along an offset extension or shoulder 34 so as to lie within a rib 35 or the like, said lugs having suitable engagement with said rib, as by means of a spring follower arrangement 36, to bear upon said 35 rib and retain said cover in engagement with the casing 14. Said follower arrangement comprises preferably a spring pressed face or screw which has slidable engagement with a head 37 of a screw 38, whereby it is secured to said lug. While the rib 35 is extended entirely along the free edge of said casing as shown, it is slotted as at 39 to receive said follower. When the cover is detached from said casing, the pressure upon 40 the follower screw caused by abutment of the flange 40 of said offset extension against the edge of the rib being released, the spring elongates, moving the follower screw outwardly of the head 37. Therefore to permit of proper engagement of said follower with said rib, a bevel or cam face 41 is formed thereon at said slot, thereby permitting said follower to ride up on to the dwell 42. Since in the preferred arrangement, I 45 provide a pair of supports or followers, the

dwell can be made approximately 180° as shown in Fig. 4, thereby insuring a certain and continuous interlock of said parts, a result which is facilitated by the spring-pressed follower. At the side of the slot opposite to the bevel 41, a stop or lug 43 is provided to limit the movement of said followers when the same abut thereon. While the fluid container can be made of any suitable material, it is preferably formed of 70 metal so as to absorb more readily the heat of the lamp. But such construction permits the same to be mounted upon the screws 38 as by being sprung therebetween. Moreover, the container can likewise be readily removed in the same manner, thereby permitting the lamp to operate for the sole purpose of giving light, and consequently at a lower temperature. It will be seen therefore that the cover 32 is readily engaged or 75 disengaged from said container as by means of a rotational movement, and that a resilient engagement is provided which takes care of expansion resulting from changes 80 in the temperature of the glass. Moreover, said cover provides in conjunction with said casing a more uniform and accurate means for controlling the character or temperature of the heat zone about said lamp and the rate of evaporation of the fluid from the 85 container 12. This result is effected by providing for a passageway for the hot gases 90 in the temperature of the glass. Moreover, said cover provides in conjunction with said casing a more uniform and accurate means for controlling the character or temperature of the heat zone about said lamp and the rate of evaporation of the fluid from the 95 container 12. This result is effected by providing for a passageway for the hot gases 100 through the device which takes the form preferably of a plurality of openings 44 within said casing and openings 45 co-operating therewith within said cover. As the rate of evaporation depends not only upon the temperature within said casing, but also upon the pressure and the humidity of the 105 gases therein, which in turn depends upon the freedom of the circulating gases, the rate of evaporation may be predetermined as by fixing the area and location of said openings.

My dispenser is arranged to be mounted in normal downwardly directed position or in an upwardly directed manner as shown in Fig. 3. For securing the latter object, said container is pivotally mounted upon the pivots or screws 38, and at a point well above the center of gravity of the container. Said container is thus tiltable upon said cover, permitting the container to be filled with fluid by holding said cover in the position shown in Fig. 1 and then inverting the same for mounting upon the casing, the lamp passing through the inner wall 13 of said container as before. The specific arrangement of said container relatively to the heating unit is such as to be retained in substantially the same relation to the heating unit, as to the filament of the lamp, whether the dispenser is used in the upward or downward position, thereby insuring a uniform operation or evaporation 11 of the fluid in the two positions.

The construction lends itself directly for ornamental or aesthetic purposes as well as the utilitarian functions set forth above. Thus the outer globe or shell may be made to simulate a rose or other attractive object. Also it will be obvious that since the liquid container may be snapped into or out of place in the cap or cover, it may be removed readily when the device is to be employed for lighting purposes.

I claim:

1. The herein described electric vaporizer comprising, in combination, a two-part casing, one of the parts including a standard lamp base whereby the casing may be inserted into any standard socket, a heating unit within the casing and communicating electrically with said base, and a fluid container adjacent to the heating unit and carried by the other part of the casing.

2. An electric vaporizer comprising, in combination, a casing having a base for insertion into any standard lamp socket, a heating unit carried within the casing and in electrical communication with said base, and a fluid container also within the casing and adjacent to the heating unit.

3. In a dispenser, the combination of a heating unit, a fluid container mounted adjacent thereto, and a casing pivotally supporting said container and controlling the rate of evaporation of the fluid therein.

4. The combination as in claim 3 wherein said casing comprises a plurality of parts having resilient means for engaging each other.

5. The combination as in claim 3 wherein said casing comprises a plurality of parts, one of which supports said heating unit while the other supports said container.

6. In a dispenser, the combination with a heating unit and a fluid container mounted adjacent thereto, of a casing having a plurality of parts, one of which supports said container and has lug means for engaging the other part, said other part having a rib to

co-operate with said lug thus retaining said casing parts in engagement, said lug means comprising a spring pressed follower, while said rib is provided with stop means co-operating therewith to govern the movement therealong.

7. In an electric vaporizer, a self-contained casing having means for direct electrical connection with any standard lamp socket, a heating unit within the casing and in electrical communication with said connection means, and a fluid container adjacent to said heating unit and supported tiltably upon and within said casing, whereby the container adapts itself automatically to holding position irrespective of the direction in which the casing is projected into said socket.

8. A device as set forth in claim 7 in which the container is held from tilting while in operation.

9. A device as set forth in claim 7 in which the heating unit serves to hold the container from undesired tilting.

10. In an electric vaporizer, a two-part casing, a heating unit carried by and within one of the parts, the other part being attachable to and separable from the part first mentioned, and a fluid container supported by said other part and tiltable with respect thereto when the two casing parts are separated.

11. A construction as set forth in claim 10 in which the container embraces the heating unit and is thereby held from tilting when the casing parts are assembled.

12. A self-contained electric vaporizer adapted for direct insertion in any one of several different directions into a standard lamp socket and including within it a fluid container so supported as to carry automatically open top upward irrespective of the direction of insertion.

In testimony whereof I affix my signature.

EDWARD RITTER.
